(57) **CLAIM**

We claim the ornamental design for a cover for portable computer, as shown and described.

DESCRIPTION

FIG. 1 is a rear elevation view of a cover for a portable computer, showing our new design;

FIG. 2 is left side elevation view thereof;

FIG. 3 is a top plan view thereof;

FIG. 4 is a right side elevation view thereof;

FIG. 5 is a bottom plan view thereof;

FIG. 6 is a front elevation view thereof;

FIG. 7 is a perspective view thereof, in a closed position; and,

FIG. 8 is a perspective view thereof, in an open position.
